UNITED STATES PATENT OFFICE.

THOMAS W. HAMILTON, OF SPRINGFIELD, MASSACHUSETTS.

DESIGN FOR A BEDCLOTHES-HOLDER.

SPECIFICATION forming part of Design No. 33,523, dated November 6, 1900.

Application filed October 11, 1900. Serial No. 32,787. Term of patent 14 years.

To all whom it may concern:

Be it known that I, THOMAS W. HAMILTON, a citizen of the United States of America, and a resident of Springfield, in the county of 5 Hampden and State of Massachusetts, have invented and produced a new and original Design for Bedclothes-Holders, of which the following is a full, clear, and exact description.

Reference is to be had to the accompanying drawings, in which the bedclothes-holder of the new design is illustrated, Figure 1 being a side view of the same, and Fig. 2 a plan view.

As shown in the drawings, the leading 15 characteristic and essential feature of my design consists in the holder comprising the frame of a partial trapezium form, which has the shorter side thereof, which is parallel with the back *a*, non-continuous or broken 20 and has the pair of upper and lower circular eyes *b b*, which are in planes right angular to that occupied by the frame proper, and the planes of said eyes are convergent the one relatively to the other.

25 The upper and lower members *c c* merge

into the back member *a* on curves, as indicated at *e*, and they merge into the front separated vertical members *d d* on curves *f*, while the eyes *b b* are joined to the said members *d d* on approximately quadrantal curves, as 30 shown at *i*. The approached faces of the said eyes *b b* have ratchet-like notches or serrations *g g*.

The whole device is constituted by a single length of round wire bent into the form of 35 the frame, having the terminal eyes in planes angular thereto, as shown.

Having thus described my invention, what I claim, and desire to secure by Letters Patent, is—

40 The design for a bedclothes-holder substantially as herein shown and described.

In testimony whereof I have hereunto signed my name in presence of two subscribing witnesses.

THOMAS W. HAMILTON.

Witnesses:

JOHN C. McCARTHY,
WM. S. BELLOWES.
